(57) **CLAIM**

The ornamental design for a pantiliner, as shown and described.

DESCRIPTION

FIG. 1 is a top perspective view of a pantiliner showing our new design;

FIG. 2 is an enlarged perspective view of the portion of the pantiliner within the circle 2 in FIG. 1;

FIG. 3 is a top plan view of the pantiliner;

FIG. 4 is a bottom plan view of the pantiliner;

FIG. 5 is an enlarged perspective view of the portion of the pantiliner within the circle 5 in FIG. 4;

FIG. 6 is a side elevation view of the pantiliner;

FIG. 7 is an enlarged cross sectional view of the pantiliner taken along the line 7—7 in FIG. 3; and,

FIG. 8 is an end elevation view of the pantiliner.
